(57) **CLAIM**

The ornamental design for a cooler accessory, as shown and described.

DESCRIPTION

FIG. 1 is a top, front perspective view of another implementation of a cooler accessory;

FIG. 2 is a front view thereof, the rear view being a mirror image;

FIG. 3 is left side view thereof, the right side being a mirror image; and,

FIG. 4 is top view thereof, the bottom view being a mirror image.

The broken lines in the drawings disclose unclaimed portions of the cooler accessory only, and form no part of the claimed design.

1 Claim, 4 Drawing SheetsFIG. 1

FIG. 2

FIG. 3

FIG. 4
